B. F. FREEMAN.
RECEPTACLE CLOSURE,
APPLICATION FILED JUNE 17, 1916.

1,220,085.

Patented Mar. 20, 1917.

UNITED STATES PATENT OFFICE.

BENJAMIN F. FREEMAN, OF LONG ISLAND CITY, NEW YORK.

RECEPTACLE-CLOSURE.

1,220,085.

Specification of Letters Patent. Patented Mar. 20, 1917.

Application filed June 17, 1916. Serial No. 104,178.

To all whom it may concern:

Be it known that I, BENJAMIN F. FREEMAN, a citizen of the United States, residing at Long Island City, in the county of 5 Queens and State of New York, have invented new and useful Improvements in Receptacle-Closures, of which the following is a specification.

This invention relates to receptacle 10 closures and has to do particularly with closures for locking the receptacle from the inside thereof so that the interior of the receptacle cannot be reached except by the destruction of the receptacle.

15 The invention also relates particularly to closures and closure fastenings for toy banks and provides a novel closure and fastening for use with the ordinary metal receptacles of commerce such as are used in the packaging and distribution of food 20 products. These receptacles, when empty of their contents, may be converted into toy banks by the addition of this novel closure.

One object of the invention is to provide 25 a metallic can closure having locking means for engagement with the receptacle on which the closure is adapted for use.

A further object of the invention is to 30 provide a simple and inexpensive device for locking a can closure in such a manner that it may be opened only by the release of a latch within the closure.

Other details of the invention will be 35 further explained and set forth in the accompanying specification and claims and illustrated in the accompanying drawing in which—

Figure 1 represents a top plan view of the 40 closure and the locking bolts applied to a receptacle which is circular and has a circular opening for the reception of the closure.

Fig. 2 is a sectional view taken on the line 2—2 of Fig. 1 and representing the position of the closure and the locking bolts 45 with respect to the receptacle, the fastening device for locking the bolts in position being illustrated in its locked position.

Fig. 3 represents the locking device for 50 fastening the bolts in position, and

Fig. 4 represents the tube or collar 55 through which the locking device for the bolts is adapted to extend and on which said device engages to prevent the removal of the bolts.

Referring to the drawings 1 represents a metal receptacle of commerce such as is

commonly used in the sale of canned vegetables, syrups and fruits. The top surface of this receptacle is provided with an opening 2 which is illustrated as circular in outline. The closure for this receptacle is provided with a main central portion 3 having the peripheral rim or wall 4 which in turn has an annular flange 5 adapted to engage with and rest on the top surface of the receptacle. Centrally located in the portion 3 of the closure is an opening 6 adapted to receive a tubular collar 7 having a flange 8. As illustrated in the drawing this flange is adapted to rest on the portion 3 of the closure and the tubular collar is extended downwardly through the opening 6 into the interior of the receptacle. The flange may be secured in position by any suitable means such as by soldering or may merely rest in 65 position and be retained in place by the fastening bolts as will be presently described. The peripheral rim 4 of the closure has a plurality of openings therethrough for the reception of the ends of the locking 70 bolts 9 which extend across the surface 3 of the closure. As illustrated it will be observed that these bolts have a centrally located opening 10 adapted to be in alinement with the opening 6. In the use of this closure the bolt members 9 are slid through the opening in the peripheral rim first on one side thereof until the opposite end of the bolt members may be inserted into the side 75 of the rim 4. When both ends of the bolt members are thus engaged with the openings in the rim the ends project beyond the rim and beneath the top surface of the receptacle effectually preventing the removal of the closure until the bolt members are 80 withdrawn from the openings in the closure rim. When the bolt members are in their locking position the opening 10 in each bolt member is in alinement with the opening 6 of the closure and the tubular collar 7 therein, the bolt members retaining this collar in position and passing across the top of the flange 8 thereof. The parts are now in 85 position for the reception of the device 11 for locking the bolts in position. This device is inserted through the openings 10 and the tubular collar 7 and comes into its locked position by engaging the extreme inner end of the collar 7. In the preferred 90 form as illustrated in the drawing the device 11 completely closes and covers the opening 10 in the bolts and is formed of 95

spring metal and with the recurved ends 11^a for engaging the end of the collar 7 and preventing the withdrawal of the device 11.

The invention is peculiarly fitted for use 5 as a locking closure for toy banks in which it is desired to prevent access to the bank until it is the desire of the owner to destroy the same. For this purpose the closure surface 3 is provided with the opening 12 and 10 chute 13 which in turn may be provided with a device for preventing the return escape of the coin.

The closure may be formed separately 15 from the receptacle and sold as an advertising novelty for use with the receptacle and the simplicity and low cost of manufacture make it possible for producers of food products to offer this closure as inducement for the purchase of the original receptacles with 20 their food contents.

From the foregoing it will be clear that this invention provides an inexpensive and simply constructed can closure and locking device therefor which may have use as adapted 25 to any receptacle for which said closure may be used. Changes in construction, relative location of the parts and material may be made without departing from the scope of the invention.

30 What I claim is:—

1. The combination with a receptacle provided with an opening and a closure therefor of a fastening device for locking said closure in its closed position comprising a substantially rigid bar member extending from 35 said closure, beyond the same and engaging the inner surface of said receptacle, and a locking member engaging with said bar member to hold the same in fixed relation 40 with respect to said closure and said receptacle.

2. The combination with a receptacle provided with an opening and a closure therefor of a fastening device for locking said closure 45 in its closed position comprising a substantially rigid bar member extending from said closure, beyond the same and engaging said receptacle, and a locking member engaging with said bar member to hold the same, in 50 fixed relation with respect to said closure and said receptacle, said locking member extending through said closure and locking on the inner side thereof.

3. The combination with a receptacle provided with an opening and a closure therefor of a fastening device for locking said closure in its closed position comprising a substantially rigid bar member extending across 55 said closure and having its ends projecting beyond either side thereof and engaging the inner surface of said receptacle, and a locking member engaging with said bar member and holding the same in fixed relation to said closure and said receptacle.

60 4. The combination with a receptacle pro-

vided with an opening and a closure therefor of a fastening device for locking said closure in its closed position comprising a substantially rigid bar member extending across 70 said closure and having its ends projecting beyond either side thereof, said ends engaging with said receptacle, and a locking member engaging with said bar member and holding the same in fixed relation to said closure and said receptacle, said locking member extending through said closure and being subject to release only from the inner side 75 thereof.

5. The combination with a receptacle provided with a circular opening and a closure 80 therefor of a fastening device for locking said closure in its closed position comprising a substantially rigid bar member extending diametrically across said closure and having its ends projecting beyond said closure and 85 engaging with said receptacle, said bar and said closure each having an opening therethrough, and a locking member extending inwardly through the opening in said bar member and said closure and latching on the inner side thereof to prevent endwise movement of said bar members.

6. The combination of a receptacle closure having an opening therethrough of a substantially rigid bar member extending across 95 said closure and having an opening therethrough and its ends extending beyond said closure, and a locking member extending through said bar member and said closure and latching on the side of said closure opposite 100 from said bar member.

7. The combination of a receptacle closure having a main portion and a rim wall extending at an angle to said main portion, said rim wall being provided with an opening therethrough, and said main portion having an opening therethrough, a substantially rigid bar member extending across the main portion of said closure and having an opening therethrough and its ends projecting through said openings in said rim wall, and a locking member extending through the opening in said bar member and through the opening in said closure and latching on the side of the closure opposite 115 to said bar member.

8. The combination with a receptacle provided with a circular opening therein and a closure therefor of a fastening device for locking said closure in its closed position comprising a bar member extending diametrically across said closure and having its ends beyond said closure and engaging with said receptacle, said bar member and said closure each having an opening therethrough, a tubular member extending from said opening in said closure downwardly into said receptacle, and a locking member extending inwardly through said bar member and through said tubular member and 120 125 130

latching on the inner end thereof, said locking member having spring hooked ends for engagement with the end of said tubular member.

- 5 9. The combination of a receptacle provided with a substantially circular opening the rim of which is spaced inwardly from the lateral edge of the receptacle, a closure therefor having an annular wall arranged to extend into said opening for frictional engagement with said rim to retain said closure in the closed position, said annular wall of the

closure being perforated, a fastening bar extending through said perforations to engage the under surface of said receptacle rim, 15 and a locking member engaging said bar and closure.

In testimony whereof I have hereunto set my hand in presence of two subscribing witnesses.

BENJAMIN F. FREEMAN.
